UNITED STATES PATENT OFFICE.

JAMES CECIL McDougall, of MONTREAL, QUEBEC, CANADA.

BUILDING WALL.

Application filed December 1, 1923. Serial No. 677,999.

To all whom it may concern:

Be it known that I, JAMES CECIL McDougall, a subject of the King of Great Britain, and resident of the city of Montreal, in the Province of Quebec and Dominion of Canada, have invented certain new and useful Improvements in Building Walls, of which the following is a full, clear, and exact description.

10 This invention relates to new and useful improvements in building walls, and the object of the invention is to provide a building wall, which will be inexpensive, strong, stable and rigid, and which will be provided 15 with horizontal air spaces or chambers for insulating purposes.

Another object is to provide a wall of hollow construction, in which no mortar joint extends through the wall.

20 A further object is to provide a brick wall of hollow construction, which will be easily back plastered and on which plaster will be laid directly on the wall without the use of furrings, lath or the like.

25 In my invention, the wall consists of three or more brick partitions bonded together in such a manner as to form parallel rows of horizontal air spaces or channels sealed from one another by the bonding courses.

30 In the drawings:—

Fig. 1 is an isometric view of a wall built of three partitions with two rows of horizontal air spaces.

35 Fig. 2 is a section of a modified construction of the wall shown in Figure 1.

Fig. 3 is a sectional elevation of a three partition wall with horizontal air spaces of equal width.

40 Fig. 4 is a section of a wall built according to my invention having four partitions and three rows of horizontal air spaces.

Fig. 5 is a modification of the wall shown in Figure 4.

45 Referring more particularly to the drawings, the walls are built of standard brick, in which the width of brick plus one mortar joint is equal to the length of the brick, which also equals three times the thickness of the brick plus two mortar joints. In

50 Figure 1, the bottom course 11 is a bonding course of headers laid on their sides or rowlock position. On the top of this bonding course and forming part of the face of the wall is laid four courses of stretchers 12

55 laid on the flat or natural bed of the bricks and their length lying in the longitudinal

direction of the wall. On the top of the courses 12 is laid another course of headers 11^a. On the inside end of the headers 11 is laid a course of brick stretchers 13 laid on their sides or in the rowlock position, end to end, thus leaving a space 14 between the face bricks 12 and the intermediate partition, as the width of a brick plus the thickness of a brick is less than the length of a brick.

60 The inside partition comprises two stretcher courses of brick 15 laid in the row lock position, with their length extending in the longitudinal direction of the wall. This inside partition is laid so that the distance from the outside of the intermediate partition to the inside face of the inside partition is equal to the length of a brick. The bonding course 16 bonds the intermediate partition to the inside partition and comprises a course of headers laid on the flat

65 or natural bed of the brick. On the top of this bonding course are laid two rows of rowlock stretchers 15, the upper edge of the top course being level with the upper edge of the headers 11^a. Between the bonding courses and adapted to form a part of the intermediate partition is laid a course of stretchers or brick disposed on their sides with their length running in the longitudinal direction of the wall. A space 17 is left

70 between the inside partition and the intermediate partition. By repeating this method of laying the partitions, a wall of any height may be built having a double row of horizontal air chambers superimposed one

75 over the other and sealed from one another by means of the bonding courses. As will be seen from the drawing, no mortar joints extend from one side of the wall to the other,

80 thus the conduction of moisture from the face of the wall to the inner face or back of the wall through the mortar joints by capillary action is prevented. In Figure 2, which shows a modified construction of the

85 wall shown in Figure 1, both the front and back bonding courses, designated 18 and 19 respectively, comprise courses of headers laid on their sides, and between the headers and forming the front and back partitions of the

90 wall are three courses of stretchers 20 laid on their sides. The inner partition is of the same construction as shown in Figure 1, that is, with a course of stretchers 13 laid on

95 their sides between each row of headers. This construction forms a double row of chambers 21 and 22 of equal width, said

rows being parallel with one another and sealed from one another by the bonding courses.

In Figure 3, which shows a modification of the wall shown in Figure 1, the headers 11^b are laid on their natural bed and the stretcher courses 17^a in the front and back partitions are also laid on their natural bed with their length extending in the longitudinal direction of the wall. The intermediate partition is similar to that shown in Figure 1.

In Figure 4, the wall is built of four partitions. The bonding courses 23 between the intermediate partitions comprise courses of headers laid on their sides and the bonding courses 24 between the intermediate partitions and the outer and inner partitions comprise headers laid on their sides or rowlock position. The outer and inner partitions are built exactly alike, that is, with four courses of stretchers laid on their natural beds between the bonding courses. The intermediate partitions are also alike, each having a course of stretchers 25 between each bonding course. This construction forms three parallel rows of horizontal air spaces or chambers superimposed one above the other and sealed from each other by the bonding courses.

In Figure 5, the wall is built of four partitions, with the bonding courses comprising headers 26 between the partitions, said headers consisting of bricks laid on their sides. Between the headers or bonding course and forming the front and inner partitions of the wall, three courses of brick stretchers 27 are laid on their sides. The intermediate partitions are of the same construction as the partition shown in Figure 1, that is, with a course of stretchers 28 laid on their edges between each bonding course. This construction forms three rows of horizontal chambers of equal width, said chambers being situated one above the other and sealed from one another by the bonding courses.

The construction of the wall is very simple and the chambers may be back plastered, as

shown at 29. The inner partition may be provided with a layer of plaster 30, which may be laid directly on the brick without the use of laths, furrings or the like. If further insulation is required, the chambers may be filled with mineral wool, cork or like insulating material, as the building of the wall progresses.

In constructing the wall, as disclosed, it will be seen that both sides of each intermediate partition and also of the front and inner partitions can be easily and readily pointed, as there is plenty of space between said partitions. Terra-cotta brick or the like may be used in the construction of the partitions.

Slight modifications may be made in the construction of the wall without departing from the spirit of the invention.

Having thus described my invention, what I claim is:

1. A hollow wall constructed of brick comprising three or more parallel brick partitions spaced from one another, vertically spaced bonding courses connecting each pair of adjacent partitions and extending the full length of the latter, the bonding courses of adjacent series being staggered vertically with relation to each other so that no joint between the partitions extends from one side of the wall to the other.

2. A hollow wall constructed of brick comprising three or more parallel brick partitions separated from one another by an air space, a series of vertically spaced bonding courses of brick between each two adjacent partitions and forming part of adjacent series of said partitions, said bonding courses being staggered vertically with respect to one another and arranged to extend from end to end of the wall to form substantially horizontally disposed air chambers, said air chambers being so positioned that no brick work extends through the wall without being protected by an air chamber.

In witness whereof, I have hereunto set my hand.

JAMES CECIL McDougall.
